UNITED STATES PATENT OFFICE.

HARRY E. WARDEN, OF DETROIT, MICHIGAN.

PAVING-BLOCK.

1,156,117.

Specification of Letters Patent.

Patented Oct. 12, 1915.

Application filed April 17, 1915. Serial No. 21,957.

To all whom it may concern:

Be it known that I, HARRY E. WARDEN, a citizen of the United States of America, residing at Detroit, in the county of Wayne 5 and State of Michigan, have invented certain new and useful Improvements in Paving-Blocks, of which the following is a specification, reference being had therein to the accompanying drawings.

10 This invention relates to paving blocks, and more particularly to wood blocks laid upon a prepared foundation and maintained in place by a filling material, as tar, asphaltum or cement.

15 The primary object of my invention is to furnish paving blocks with novel spacing members, which can be placed in engagement with the blocks to properly space the same irrespective of the size of the blocks 20 the spacing members compensating for size inequalities incurred by shrinkage and imperfect cutting of the block.

Another object of this invention is to provide paving blocks with spacing members 25 adapted to prevent lateral displacement of a block relative to adjoining or confronting blocks, the spacing members having novel guards that protect the same from tar or other filling material, thus permitting of 30 the blocks being relaid or utilized for repair purposes.

A further object of this invention is to provide simple and effective means for spacing and interlocking wood paving 35 blocks, whereby the blocks cannot become vertically displaced relative to each other, the interlocking means distributing a load upon any particular block to adjoining blocks, and thereby preventing sunken or 40 irregular portions in a pavement.

The above and other objects are attained by a mechanical construction that will be hereinafter specifically described and then claimed, and reference will now be had to 45 the drawing wherein—

Figure 1 is a perspective view of a paving block in accordance with my invention; Fig. 2 is a side elevation of a plurality of blocks as laid upon a prepared foundation; 50 Fig. 3 is a plan of the same; Fig. 4 is a detail sectional view illustrating a guard or shield for a spacing member of a block; Fig. 5 is a detail sectional view illustrating spacing and interlocking members of blocks; 55 Fig. 6 is a cross sectional view taken on the line VI—VI of Fig. 5, and Fig. 7 is a per-

spective view of a spacing and interlocking member.

In the drawing, the reference numeral 1 denotes a rectangular wood paving block 60 which has one end wall 2 thereof and one side wall 3 thereof provided with spacing members 4, said members being disposed to properly space the walls 2 and 3 relative to the walls of adjoining blocks, as shown in 65 Fig. 3. The spacing members are preferably in the form of large headed tacks which are driven into the blocks a desired distance. For this purpose a suitable driving machine can be employed which has a predetermined 70 stroke or blow that will simply drive the spacing members a known distance, consequently blocks that are not uniform in size will have the spacing members thereof compensate for the size inequalities, thus 75 permitting of various sizes of blocks being evenly laid and properly spaced relative to adjoining blocks.

To prevent tar or other filling material 80 that is generally placed in the cracks or interstices between the blocks from injuring the spacing members for repaving purposes, sleeves 5 can be placed upon the spacing members and supported by the heads thereof, as clearly shown in Fig. 4.

85 Spacing and interlocking members are shown in Figs. 5 to 7 inclusive, said members being in the form of nails 6 which are driven into side walls of the blocks, and these spacing and interlocking members are 90 used in conjunction with spacing members 4 at end walls of blocks. The outer ends of the nails 6 terminate in substantially S-shaped shanks 7 adapted to slide one into the other and besides spacing the blocks 95 apart, these S-shaped shanks prevent vertical displacement of one block relative to another. The interlocking members connect a series of blocks whereby a load upon any particular block is distributed to the 100 adjoining blocks, thus maintaining an even surface upon a pavement composed of blocks connected and laid in accordance with my invention.

105 As shown in Fig. 5, sleeves 8 may be used in connection with the interlocking members to shield the same from filling material placed between the blocks.

I am aware that paving blocks have been provided with ribs, tongues and grooves, 110 dowel pins and other spacing and connecting members, but in each and every instance

there is a sacrifice of lumber or material, creating a waste of little value besides necessitating a prescribed system or method of laying the blocks. My invention not only permits of undersize or oversize blocks being used, but eliminates any waste of material.

The preferred embodiments of my invention have been illustrated, but it is to be understood that the structural elements are susceptible to such variations and modifications as fall within the scope of the appended claims.

What I claim is:—

- 15 1. A pavement composed of blocks, spacing members carried by walls of said blocks and abutting walls of other blocks, and shields on said spacing members between said blocks.
- 20 2. A pavement composed of blocks, inter-

locking members connecting said blocks, and shields on said interlocking members between said blocks.

3. A pavement composed of blocks, and block equalizing and spacing members 25 adapted to be forced in an end wall and side wall of each block and having heads abutting and bracing end and side walls of adjoining blocks, said members being forced in said blocks to a depth to compensate for 30 irregularities in the size of said blocks, whereby undersized blocks have side and end walls braced by adjoining blocks.

In testimony whereof I affix my signature in presence of two witnesses.

HARRY E. WARDEN.
